UNITED STATES PATENT OFFICE.

CHARLES J. TRAVERS, OF PORT WASHINGTON, WISCONSIN, ASSIGNOR TO GILSON MANUFACTURING CO., OF PORT WASHINGTON, WISCONSIN, A CORPORATION OF WISCONSIN.

CHAIR IRON.

Application filed April 14, 1922. Serial No. 552,777.

To all whom it may concern:

Be it known that I, CHARLES J. TRAVERS, a citizen of the United States, and resident of Port Washington, in the county of Ozaukee, and State of Wisconsin, have invented certain new and useful Improvements in Chair Irons; and I do hereby declare that the following is a full, clear, and exact description thereof.

10 The invention relates to chair irons and more particularly to that type on which Patent No. 1,332,402, was granted on March 2, 1920, to Olaus O. Krabol.

15 Among the various features of improvement is a modification of the clamps that grip the legs. These are provided with lugs depressed from the clamps and operating when the clamps are in interlocked position to prevent the fingers of the clamps which 20 result from longitudinal slots, from being laterally deflected. These lugs are few in number, simple, easy to make, and have the primary object of giving great strength to the clamps, so that for a minimum of 25 weight of parts and an especial thinness of metal, a more durable clamping action on the legs is produced.

30 The invention also contemplates a modification of the bottom plate, whereby a plurality of bosses are produced by depressing the metal, the bosses being apertured and receiving the screws by which the plate is secured to the legs.

35 An object of the boss structure is strength, lateral movement of a leg with respect to the plate being prevented. The head of the screw being received in the bosses, a substantially smooth lower surface is produced, so that there are no projecting edges. Four 40 of the bosses are adapted to be received between flanges of the clamps. This is effective to prevent relative movement between the clamps and the plate, as this movement could not result unless the clamps rode up 45 on the surface of the bosses.

50 Other objects of the improved structures are simplicity of parts, of which there is a minimum number. The spindle barrel common in the prior art is unnecessary in the novel construction, the screw on which the chair is supported being received by and rotatable among the clamps which are deformed in such manner that when interlocked, they provide what is substantially

a cylinder. The clamps are cut away adjacent their top edge and the top plate is provided with a downwardly directed flange resting on the cut away edges. The clamps rest upon the bottom plate so that the structure is exceedingly simple. 55

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims. 60

65 In the accompanying drawing, I have illustrated one complete example of the physical embodiment of the present invention constructed according to the best mode I have so far devised for the practical application of the principles thereof, and in which: 70

75 Figure 1 shows a plan view of the invention.

Figure 2 is a section on the line 2—2 thereof. 80

Figure 3 is a bottom view, the legs being broken away.

Figure 4 is a horizontal section.

85 Figures 5 and 6 are details of clamps.

Bottom plate 10 is substantially of disk like shape, but apertured centrally and provided with radial arms 11, at the end of which are upwardly directed apertured bosses 12, thru which screws 13 are directed into legs 14 of the chair. The bottom plate is also provided with bosses 15, apertured for the reception of screws 16. Clamps 17—17' have slots 18 therein, so that fingers 19, 20 and 21 are produced. Clamps 22—22' are somewhat similar to clamp 17 but are provided with slots 23 and 24 in the lower part thereof, producing fingers 25, 26 and 27. Each of the clamps has a laterally directed flange 28. Clamps 17—17' are provided with lugs 29—29', which are depressed from the metal and clamps 22—22' are provided with lugs 30—30'. The clamps are assembled in the manner directed in the above identified patent, and fingers 19 and 21 contact with lugs 30—30' and are prevented, thereby, from outward movement. Fingers 25 and 27 are likewise prevented from out- 100

105

ward lateral movement by lugs 29—29'. Thus an effective rigid structure is provided.

The clamps are provided with longitudinal central deformations 31 which are 5 adapted to receive a screw supporting the chair. The structure is designed to eliminate all need for a spindle barrel or hub, which in the prior art was provided to encase the screw.

10 It will be noted that flanges 28 contact with bosses 15. The bosses function therefore, to prevent relative movement between bottom plate 10 and the clamps, as such movement would necessitate the riding up 15 of flanges 28 on bosses 15.

Clamps 17—17', 22—22' are cut away adjacent their top edges, and an annular flange 32 is downwardly directed from top plate 33, and contacts with the curved central portions 20 of the clamps. Top plate 33 is provided with an outer downwardly directed flange 34 and is apertured to receive screws 35, by which the plate is secured to legs 14.

It will be noted that the clamps rest on 25 lower plate 10.

I claim:

1. The combination of a pair of parallel clamps, each of said clamps having a pair of slots therein whereby three fingers are 30 formed on each of said clamps, a second pair of oppositely disposed clamps each having a pair of parallel slots therein, whereby three fingers are formed on each of said last mentioned clamps, said last mentioned pair of clamps being disposed at right angles to 35 said first mentioned pair of clamps and fitting in the slots of said first mentioned pair of clamps, said first mentioned pair of clamps fitting in the slots of said last mentioned pair of clamps, whereby all of said 40 clamps are in interlocked relationship, a pair of lugs on the outer face of each of said clamps, adjacent the outer fingers of the other clamps, said lugs being outwardly disposed with respect to said fingers, and 45

immediately adjacent thereto and preventing outward movement of said fingers.

2. In a chair iron, the combination of a plurality of interlocking clamps, each of said clamps being cut away centrally along 50 its top edge and a top plate having a central opening therein and a central annular depending flange resting on said clamps along their cut away portion.

3. In a chair iron, the combination of a 55 plurality of interlocking clamps, each of said clamps being longitudinally deformed centrally and cut away centrally to form a surface conforming to a central cylindrical bore along its top edge, and a top plate 60 having a central annular depending flange contacting with the central cut away edges of said clamps.

4. The combination of a pair of oppositely disposed clamps, each having a pair of slots therein forming a central finger and an outer finger on each side of said central finger, a second pair of oppositely disposed clamps, each having a pair of slots therein forming a central finger and an outer finger 70 on each side of said central finger, said second pair of clamps being received within the slots of said first mentioned pair of clamps and extending at right angles to said first mentioned pair of clamps, said 75 first mentioned pair of clamps lying in the slots of said second mentioned pair of clamps whereby all of said clamps are in interlocked relationship, a longitudinal flange inwardly directed from the side edges 80 of each of said clamps, a base plate, a plurality of bosses thereon, each of said bosses being received between a pair of flanges on said clamps.

In testimony that I claim the foregoing I 85 have hereunto set my hand at Port Washington, in the county of Ozaukee and State of Wisconsin.

CHARLES J. TRAVERS.
